CLAIM

The ornamental design for a portable removable bicycle stand, as shown and described.

DESCRIPTION

FIG. 1 is a top, front and side perspective view of a portable removable bicycle stand showing my new design, it being understood that the broken lines are for illustrative purposes only and form no part of the claimed design;

FIG. 2 is a front perspective view of the bicycle stand;

FIG. 3 is a top plan view of the bicycle stand;

FIG. 4 is a bottom plan view of the bicycle stand;

FIG. 5 is a rear elevational view of the bicycle stand;

FIG. 6 is a rear perspective view of the bicycle stand;

FIG. 7 is a side elevational view of the bicycle stand; and,

FIG. 8 is an opposite side elevational view of the bicycle stand.
